UNITED STATES PATENT OFFICE

JOHN J. TATUM, OF BALTIMORE, MARYLAND

BRAKE SHELF FOR RAILROAD CARS

Application filed January 4, 1930. Serial No. 418,574.

In the economic administration that is now being practiced in railroad management efforts are being made to not only reduce the number of separate parts carried in storage and shops and division centers, but efforts 5 are directed to reduce the number of manual operations in producing and attaching parts to railroad cars. Integral devices are favored because of the liability, and tendency 10 of separate parts working loose in the service movements of cars in transit.

One of the objects of my invention is to provide a one piece brake shelf for freight cars, which will be simple in construction, and 15 easy in attachment, cheap in manufacturing cost, and provided with means to drain cinders and the elements from the foot contacting surface, and provided with a foot guard to prevent the trainmen from slipping from 20 the shelf; and with this and other objects in view my invention consists of the one piece foot shelf hereinafter set forth.

In the drawings:

Figure 1 is an end elevation of a freight 25 car, slightly in perspective with my improved shelf attached thereto.

Figure 2 is a top plan view of my improved shelf detached.

Figure 3 is a front elevation of Figure 2.

Figure 4 is a transverse sectional view of 30 Figure 2 taken about midway between its ends.

Figure 5 is a view similar to Figure 4 showing another embodiment of my invention.

35 The reference numeral 6 designates a freight car of approved construction, provided with the usual brake staff 7, my improved brake shelf being designated in Figure 1 by the reference letter A.

40 My improved one piece shelf comprises the foot rest or shelf 8 having at its rear edge an upstanding attaching flange 9 provided with bolt or rivet openings 10 in which bolts or rivets are secured to attach the shelf to 45 a car. This foot rest or shelf 8 is provided with a depressed corrugation 11 which, preferably, decreases in depth toward the ends of the shelf, as best seen in Figure 3, and at its deepest point is provided with an exit port

50 12. I prefer to form this corrugation in the

direction of the longest dimension of the shelf. This corrugation 11 not only functions as a rigidifying beam for the shelf, but also functions as a drain through which cinders and the elements are drained from 55 the foot contacting surface of the shelf. The corrugation 11 provides a much stronger foot rest or shelf, and in this added strength compensates for the loss of metal from the upper face of the support 8 due to corrosion and 60 deterioration, thereby adding materially not only to the safety of the shelf, but to the life of the shelf in actual service.

The shelf is provided with end flanges 13 which terminate in attaching flanges 14 which 65 are provided with bolt or rivet holes 15. The flange 9, brackets 13 and flanges sustain the shelf, when in position, against downward thrusts, while the flanges 14 and brackets 13 provide against end thrusts.

The forward edge of the foot rest or support 8 is provided with an upstanding flange 16 to prevent the foot of the trainman from slipping off the support, although, as shown, in Figure 5, this flange may be omitted, if 70 desired.

The foot support preferably is provided with perforations to facilitate draining.

What I claim is:

1. A one piece brake shelf for railroad cars 80 pressed up from one piece, comprising a foot shelf, an upstanding attaching flange at the rear edge of the shelf, and a rigidifying depressed corrugation in said shelf functioning as a beam extending between the ends of the shelf.

2. A one piece brake shelf for railroad cars 90 pressed up from one piece, comprising a foot shelf, an upstanding attaching flange at the rear edge of the shelf, and a rigidifying depressed corrugation in said shelf functioning as a beam extending between the ends of the shelf, and a drain port at the bottom of said corrugation.

3. A one piece brake shelf for railroad cars 100 pressed up from one piece of metal, comprising a shelf, an upstanding attaching flange at the rear edge of the shelf, and a rigidifying depressed corrugation in said shelf

decreasing in depth toward the ends of the shelf.

4. A one piece brake shelf for railroad cars pressed up from one piece of metal, comprising a shelf, an upstanding attaching flange at the rear edge of the shelf, and a rigidifying depressed corrugation in said shelf decreasing in depth toward the ends of the shelf, and a drain port through the bottom wall of and at the deepest point in said corrugation.

5. A one piece brake shelf for railroad cars pressed up from one piece, and comprising a foot shelf having a brake staff opening therethrough, an upstanding attaching flange at the rear edge of said shelf, brackets at each end of the shelf terminating in attaching flanges, a depressed corrugation in said shelf which functions as a rigidifying beam and drain for the shelf.

6. A one piece brake shelf for railroad cars pressed up from one piece, and comprising a foot shelf having a brake staff opening therethrough, an upstanding attaching flange at the rear edge of said shelf, brackets at each end of the shelf terminating in attaching flanges, a depressed corrugation in said shelf which functions as a rigidifying beam and drain for the shelf, and an upstanding foot guard flange at the outer edge of the shelf.

7. A one piece brake shelf for railroad cars made from one piece of metal; said shelf comprising a foot shelf having a brake staff opening therethrough, an attaching upstanding flange at the rear edge of said shelf, brackets at each end of the shelf terminating in attaching flanges, a depressed corrugation in said foot shelf decreasing in depth toward each end of the foot shelf, said corrugation functioning as a rigidifying beam and drain for the foot shelf, and a drain port through the bottom wall of the said corrugation.

8. A one piece brake shelf for railway cars pressed up from one piece, comprising a perforated foot shelf, and a right angle attaching flange at the rear edge of the shelf, having a rigidifying depressed corrugation to function as a beam in the foot floor, extending between the ends of the shelf.

50 9. A one-piece brake shelf for railway cars, comprising a foot shelf having attaching means and provided with a longitudinally extending depressed rigidifying corrugation functioning as a strengthening beam.

55 10. A one-piece brake shelf for railway cars, comprising a foot shelf having attaching means and provided with a longitudinally extending depressed rigidifying corrugation functioning as a strengthening beam, said corrugation being of maximum depth at a middle point and provided with a drain opening.

60 11. A one-piece brake shelf for railway cars, comprising a foot shelf having a right angularly disposed attaching flange at the

rear edge thereof, attaching flanges at the ends thereof, an upstanding longitudinally extending safety flange at the front edge thereof, and a longitudinally extending rigidifying corrugation in the body of said shelf 70 functioning as a strengthening beam, said corrugation being of maximum depth at its center and provided with a drain port.

In testimony whereof I affix my signature.
